UNITED STATES PATENT OFFICE

109,302

DESIGN FOR A COAT TREE

Oscar Rondeau, Providence, R. I.

Application February 12, 1938, Serial No. 75,097

Term of patent 7 years

To all whom it may concern:

Be it known that I, Oscar Rondeau, a citizen of the United States of America, residing at Providence, county of Providence, State of Rhode Island, have invented a new, original, and ornamental Design for a Coat Tree, of which the following is a specification, reference being had to the accompanying drawing, forming a part thereof.

The figure is a perspective view of a coat tree showing my new design.

The dominant feature of this design is the representation of the group of animals at the base and the single animal at the top of the coat tree, as shown.

I claim:

The ornamental design for a coat tree substantially as shown and described.

OSCAR RONDEAU.
